UNITED STATES PATENT OFFICE

LOUIS A. BURCH, OF SEATTLE, WASHINGTON

ROTARY SIGNBOARD

Application filed October 27, 1928. Serial No. 315,401.

The invention is a rotary sign board comprising a plurality of sign boards rotatably mounted in a frame in combination with a plurality of sails pivotally mounted upon a frame that is rotatably mounted in the frame with the sign boards and geared to the sign board to propel the same.

The object of the invention is to provide a plurality of sign boards with means whereby they may be efficiently operated by wind.

Another object of the invention is to provide means for mounting a plurality of sign boards and means for rotating the said sign boards whereby the wind may rotate the sign boards and the rotation speed of the sign boards may be governed.

Another object is to provide a plurality of eccentrically mounted sails on a rotatable frame with bumpers to stop and hold the sails for the effective part of their cycle to produce rotation.

Another object is to provide a rotatable frame having a plurality of signs or the like on the outer surface thereof, in combination with means whereby wind may cause the said sign boards to rotate, in which gears are provided between the rotating means and the sign board frame which will cause the frame to rotate at a lesser speed than the rotating means.

A further object of the invention is to provide suitable bearings for an outdoor rotating sign board frame, and for means for rotating the same by wind, which are simple and inexpensive and at the same time efficient.

A still further object of the invention is to provide a suitable brake for a rotating frame for sign boards or the like which will automatically operate to maintain a substantially constant rotating speed.

And a still further object of the invention is to provide a rotating frame with a plurality of sign boards or the like on the outer surface thereof, in combination with means for operating the same by wind, which is of a comparatively simple and economical construction.

With these ends in view the invention embodies a frame, a plurality of sign boards on the outer surface of the frame, a stand in

which the frame is rotatably mounted, another frame also rotatably mounted on the same stand, a plurality of sails upon the said latter frame adaptable to rotate the same when acted upon by wind pressure, means whereby the said sail frame may rotate the said sign board frame, and a suitable automatically operated brake whereby the rotation of the said device may be regulated.

Other features and advantages of the invention will appear from the following description taken in connection with the drawings, wherein:

Figure 1 is a front elevation of the device.

Figure 2 is a plan view of the device.

Figure 3 is a side elevation with parts broken away.

In the drawings the device is shown as it would be made, wherein numeral 1 indicates the sign boards, numeral 2 the sails and numeral 3 the stand in which the sign boards and sails are rotatably mounted.

In the design shown the sign boards 1 are mounted upon the outer surface of a rectangular frame 4 which is made with a vertical central member 5 through which the frame is rotatably mounted in the stand 3. The frame 4 may be of any suitable design and may be constructed in any suitable manner and may have as many flat sides, upon which sign boards may be placed, as may be desired. In the design shown it is made in the form of a square and is attached to the central member 5 through arms 6 which are attached to the frame by clips 7. It is also understood, however, that the frame 4 may be attached to the central member 5 by any suitable means. The lower end of the member 5 is provided with a pin 8 as shown in Figure 3 and it will be observed that the upper end of the pin is rigidly mounted in the member 5 and the lower end is rotatably mounted in a bushing 9 in a bearing 10. The bushing is made as shown in Figure 3 so that grease or the like may be packed in the open space between the end of the bushing and the upper end of the bearing. The bearing may be provided with a cover plate 11, as shown, which will prevent rain, dirt or the like entering the bearing.

The upper end 12 of the member 5 is also

100

provided with a pin as indicated by the numeral 13 which extends to a point 14 in an opening 15, and it will be observed that the frame 4 is mounted between a lower member 16 and an intermediate horizontal member 17 of the stand 3, through the pin 8 and bearing 10 at the bottom and the pin 13 at the top.

On the upper end of the pin 13 is a gear 18 having a cup 19 on the upper side thereof and the plate 20 on the upper side of the member 17 is provided with a pin 21 that extends into the cup 19 as shown in Figure 3, so that the upper end of the pin 13 will be pivotally held. This pin 21 in the cup shaped member 19 forms the bearing for the upper end of the circular member 5 of the sign board frame 4.

The gear 18 meshes with a pinion 22 on a stub shaft 23, the lower end of which is rotatably mounted in a cup shaped bearing 24, as shown. The upper end 25 of the stub shaft 23 is rigidly mounted in a central member 26 of the sail frame 27 and between the lower end of the sail frame and the intermediate member 17 is a brake drum 28 having brake shoes 29 positioned so that they are adaptable to bear against the brake drum as the speed of the device exceeds a predetermined amount.

It will be noted that the brake shoes 29 are positioned on the end of levers 30 which are pivotally mounted upon the lower diagonal struts 31 of the sail frame 27 through pins 32 at the points 33. The levers 30 are resiliently held inward by springs 34 and their outer ends are held upward by members 35 which are pivotally attached to eyes 36 on the levers 30 and also to eyes 37 on the struts 31 at the upper end of the sail frame. It will be observed that normally the springs 34 will hold the brake shoes 29 away from the brake drum 28, however, as the speed of the sail frame increases the centrifugal motion will throw the weights 38, at the ends of the levers 30, outward and as the speed increases these weights will continue to move outward so that they will gradually force the brake shoes against the drum, which will retard the rotation of the device with increasing friction with increasing speed.

The upper end of the central member 26 of the sail frame is provided with a sleeve 39 having a bushing 40 in the end thereof and it will be observed that a pin 41, extending downward from the upper horizontal member 42 of the stand 3, will extend into the sleeve 39 and into the bushing 40 to form a bearing. This lever may also be provided with a cover as indicated by the numeral 43 if desired.

The sails 3 may be made of a flat piece of material and may be attached to the sail frame 27 by any suitable means. In the design shown a vertical post 44 is attached to the back of the sails and the lower end of this post is provided with a pin 45 which rests in a cup shaped bushing 46 in a bearing

47 which is similar to the bearing 10 of the sign board frame 4, and the upper end is provided with a sleeve 48 and a bushing 49 in which a pin 50 is rotatably held and it will be observed that this bearing is similar to the bearing at the upper ends of the central members 5 and 26. The sail frame 27 is provided with bumpers 51, which are positioned as shown in Figure 2, to limit the movement of the sails so that they will be positioned to rotate the sail frame when the frame is in any position in relation to the wind.

It will be noted that these sails are eccentrically mounted at the corners of the frame so that the wind current will automatically place the sails at the correct angle through which the greatest amount of efficiency will be obtained; and so that each sail will act independently. The sails will strike the bumpers which will stop and hold them in the correct position throughout the effective part of each cycle.

In the design shown the stand 3 is made with horizontal base members 16 upon which vertical posts 52 are mounted and it will be observed that the horizontal intermediate member 17, and also the upper horizontal member 42, extend outward from the posts and are held by diagonal braces as shown. It will be observed that these braces may be arranged as shown, or the horizontal members held to the posts, or the stand 3 constructed or supported in any other suitable manner.

It will be understood that other changes may be made in the construction without departing from the spirit of the invention, one of which changes may be in the use of other means for mounting the rotating frames in the stand, another may be in the use of other means for causing one frame to rotate by the other, or for controlling the rotation of the frame, and still another may be in the use of other means for causing the sign board frame to rotate by the wind.

The construction will be readily understood from the foregoing description. To use the device it may be constructed and assembled as shown with any suitable signs, which may be changed as desired, placed upon the boards 1 and with the device positioned where the wind may strike the sails 3. It will be noted that the wind will cause the sails to rotate the upper frame and this will in turn rotate the lower frame through the gears, and should the upper frame rotate too rapidly the centrifugal motion will throw the weights 38 outward so that the friction of the brake shoes against the brake drum will be increased and this will regulate the rotation of the frame. It will therefore be observed that this device will provide a very efficient and inexpensive method for operating a plurality of sign boards on a rotating frame, thereby providing a very simple and

inexpensive and at the same time unique advertising or display device.

It will be understood that any other suitable means may be used in combination with the device for advertising purposes as an airplane, as indicated by the numeral 53 and shown in Figure 3, which may be attached to the upper end of the pin 41 which may rotate with the sail frame 27 and the pin may also extend upward, as shown in Figure 1 and the upper end provided with a gear box 54 having a crank 55 attached to a dummy 56 so that as the device rotates the crank will operate the dummy so that it will appear as though the dummy were operating the device. It will be understood, however, that any other suitable device may be used in combination with the frames for advertising or other purposes.

Having thus fully described the invention what I claim as new and desire to secure by Letters Patent, is:

1. In a wind operated rotary sign board of the class described, a comparatively large rectangular shaped frame having a lower horizontal member, an upper horizontal member, and vertical struts connecting the said members; sign boards on the flat vertical sides of the said frame, a supporting frame, a downwardly extending pin in the center of the said lower horizontal member, a cup in the said supporting frame into which the said pin extends forming an exposed grease retaining bearing, a similar bearing at the top with the cup in the said upper horizontal member and the pin in the supporting member, a superimposed frame somewhat smaller and of similar construction, similar bearings rotatably mounting said superimposed frame in said supporting frame, a flat rectangular shaped sail at each corner of the said superimposed frame, means for pivotally mounting the said sails at both the upper and lower edges with the leading portion somewhat longer than the trailing portion, rigid vertical bars on the frame positioned to be engaged by and to form stops for the said sails, and suitable gears for operating the large frame by the superimposed frame.
2. In a wind operated rotary sign board of the character described, a box like frame, a supporting frame in which the said box like frame is rotatably mounted, a somewhat smaller superimposed box like frame also rotatably mounted in the said supporting frame and positioned above the larger frame, means for rotating the larger frame by the smaller, sign boards on the sides of the said larger frame, suitable sails rotatably mounted at both their upper and lower edges upon and at the corners of the said smaller frame and with the length of the leading portion greater than that of the trailing portion and rigid stops on the said smaller frame adapt-

ed to be engaged by the said sails throughout the entire width of the sails.

3. In a wind operated rotary sign board of the character described, a box like frame, a supporting frame, means for rotatably mounting the said box like frame in the said supporting frame, signs on the said box like frame, a smaller box like frame positioned above the said larger frame, means for rotatably mounting the said smaller frame in the said supporting frame independent of the said larger frame, means for rotating the said larger frame by the smaller frame, suitable sails rotatably mounted at both their upper and lower edges upon and at the corners of the said smaller frame and with the length of the leading portion greater than that of the trailing portion and rigid stops on the said smaller frame adapted to be engaged by the said sails throughout the entire width of the sails.

In testimony whereof I affix my signature.

LOUIS A. BURCH.
